Inventor:
Henry Fletcher

UNITED STATES PATENT OFFICE.

HENRY FLETCHER, OF PROVIDENCE, RHODE ISLAND.

IMPROVEMENT IN BRAIDING-MACHINES.

Specification forming part of Letters Patent No. 39,137, dated July 7, 1863.

To all whom it may concern:

Be it known that I, HENRY FLETCHER, a resident of the city and county of Providence, and State of Rhode Island, have invented a new and useful Improvement in the Braiding-Machine; and I do hereby declare the same to be fully described in the following specification and represented in the accompanying drawings, of which—

Figure 1 is a top view, Fig. 2 a side elevation, and Fig. 3 a vertical and longitudinal section of a braiding-machine provided with my invention, the nature of which consists in the combination of a switch-cam on the racer, with one or more pins, or the equivalent thereof, carried on the race-plate, the same being arranged in manner and for the purpose as hereinafter specified.

The object of my invention is to dispense with the guide-cap usually required over each of the gears, and within the race-circle thereof, and thus avoid the liability of such cap to turn out of place, and thereby affect the proper movements of the racers.

My invention renders the braiding-machine more certain in its operation than when made with guide-caps, and enables it to be operated with less power and friction.

In the drawings, A denotes the race-plate, provided with a series of circular openings, a b c d, which are so arranged that two, a b, open into each other and into the others, c d, by openings e e e, as shown in Fig. 1. Below these openings there is a train of gears, f f f f, there being one of such gears to each opening. A recessed cap or racer driver, g, is fastened on the upper surface of each gear and revolves with it.

Fig. 4 exhibits the driver in under side view, with its recesses h h h h for reception of the foot i of the racer B. The said racer rests on the gear, and is kept in an upright position by means of a recess, h, and that part of the base of the racer which projects into such recess. This mode of supporting the racer—viz., directly on the gear instead of on the upper surface of the race-plate—though shown in the drawings and above described, I do not claim as my invention, believing it to have been invented by Joseph Fletcher, of said Providence.

In carrying out my invention I affix to the lower part of the foot of the racer B a switch-cam or flaring wing, C, shaped as shown in top view in Fig. 5, and I also apply to the race-plate, or suitable parts thereof, guides or pins D D D, so arranged and projecting above the top face of the said race-plate that during the movements of the racer around in each of the openings e e e of the race-plate the cam or wing C, by contact with and movement against one of these pins, shall be caused to turn the racer aside more or less, and direct it from the opening in which it may be moving into the next one of such openings.

I claim—

The combination of the switch-cam C of the racer with one or more pins, D D, or the equivalent thereof, raised on the race-plate, the same being arranged so as to operate substantially in manner and for the purpose as hereinbefore specified.

HENRY FLETCHER.
